UNITED STATES PATENT OFFICE

BURNHAM C. STICKNEY, OF HILLSIDE, NEW JERSEY, ASSIGNOR TO UNDERWOOD
ELLIOTT FISHER COMPANY, OF NEW YORK, N. Y., A CORPORATION OF DELAWARE

TYPEWRITING MACHINE

Application filed May 5, 1927, Serial No. 188,988. Renewed June 4, 1928.

This invention relates to line-spacing mechanism for a typewriter. There are provided novel means for minutely varying and setting the extent of a unit of line-spacing distance within a predetermined range, and means whereby the platen may be spaced through multiples of said units.

One object of the invention is to provide such mechanism in a form that may be cheaply manufactured and installed and in a form that will harmonize with the general appearance of the typewriter to which it is attached.

Variation in the extent of a line-space-unit is secured by a connection between the usual line-space-handle and the platen including a clutch which preferably consists of a revoluble member having peripheral teeth and a toothed driver to engage and positively actuate and control said member by means of said teeth. The mechanism is so arranged that said clutch-member has a relatively large angular movement for line-spacing, and the pitch of the teeth is very fine, so that the lost-motion, if any, is practically negligible.

There is used a train of reducing gearing between said clutch-member and the platen. A feature of the invention conducing to compactness and good appearance is that the train of gearing connecting the clutch-member or its equivalent to the platen is entirely mounted upon and supported by and concentric with the platen-axle. Said train of gearing, which is therefore epicyclic in character, is further so arranged and proportioned that it may be moved from either end, that is to say, it is not self-locking in one direction; thus the platen may be rotated by means of the revoluble clutch-member through said train of gearing, and said train of gearing being capable of inverse movement, the platen may also be turned by the usual platen knob.

As herein shown, the epicyclic train of gearing includes a fixed annular gear concentric with the platen-axle and an arm keyed to the platen-axle, said arm having a pinion at its outer end meshing with said annular gear. Another pinion concentric

with and rigidly connected to said first pinion meshes with a gear rotating loosely upon the platen-axle. To the latter gear, the aforesaid revoluble clutch-member, preferably in the form of a ratchet wheel, is rigidly connected so that when said clutch-member is rotated, the platen is rotated proportionately to the relative diameters of the several gears and pinions, as will be shown. The clutch-driver is preferably in the form of a pawl or dog mounted on the end of an arm also loosely rotatable upon the platen-axle.

The clutch-mechanism and train of gears are substantially enclosed in a cylindrical shell which may surround the circumference of a flange, disk or spider, to which are rigidly connected the last-mentioned loose gear on the platen-shaft and the ratchet-wheel. This cylindrical shell, besides conducing to neatness of appearance by enclosing the gears and adjacent parts, also serves as a finger-piece whereby the platen may be rotated. Said cylindrical shell being rigidly connected to the ratchet-wheel or similar clutch-member, there is the same ratio between its extent of rotation and the resulting rotation of the platen, and as said ratio is a large one, the cylindrical shell thus serves for revolving the platen slowly to facilitate the adjustment of any portion of a work-sheet on the platen to the printing line of the typewriter.

The aforesaid pawl-arm has a reciprocatory or oscillatory movement or swing about the platen-axle; said movement being derived from a similar reciprocatory movement, but of substantially less extent, of a member or sector forming a circular rack which engages a pinion rigidly connected to said pawl-arm, said pinion being concentric with the platen-axle.

A feature of the invention is that the pawl-arm actuating-sector derives its movement directly from the operation of a slide mounted for reciprocatory movement in a plane parallel to said sector and adjacent thereto. The slide accordingly engages the sector by means of a pin or stud shiftably mounted on said slide. The position of said pin relative to the fulcrum of the sector may

therefore be shifted so that any given movement of said slide may impart a variable movement to the sector for the purpose of varying the extent of a line-space-unit or 5 any of its multiples. Novel means, to be hereinafter described and which constitute another feature of the invention, are employed to shift said pin or stud on the slide. The slide moves transversely of the axis 10 about which the sector rotates and the shiftable pin thereon is so disposed that the extent of movement of the pin for maximum stroke of the slide is bisected by a perpendicular from the sector-axis. It results from 15 this equilateral arrangement of the stroke of said pin or stud on each side of the sector-axis that there is a more near approach to a constant ratio between a line-space-unit and any multiple thereof, irrespective of the 20 adjusted extent of said unit, than has heretofore been attained. In other words should double spacing, for example, be desired, said double spacing will, to a degree not heretofore attained, approach exactly double the 25 extent of whatever line-space-unit the position of the aforesaid pin on the slide is adjusted for, it being understood that single or multiple spacing is determined by the extent of movement of said slide.

30 For determining whether the platen is to be rotated through a single line-space-unit, or a multiple thereof, novel stopping means, which engage the aforesaid slide, are used to determine the extent of movement of said 35 slide. Said novel means are embodied in a fan-shaped sector having stepped edges which serve as stops for the slide, said stops engaging a projection extending from a suitable portion of said slide. The slide may be 40 normally drawn and held against said stops by means of a spring. The fan-shaped sector, which serves as a slide-stop, is loosely mounted upon the platen-axle so that its different stepped portions which may be concentric with said axle may be selectively moved to be engaged by the slide. A handle 45 or finger-piece for manipulating the stop-sector may be formed integral with said sector, being preferably connected thereto by means of a tie so that there is formed a 50 U-shaped piece which is fulcrumed upon the platen-axle. The handle or finger-piece may have a knob which is at the side of the platen-frame, said knob being in a position 55 that is substantially the same as that of the usual shiftable knob which is used on the Underwood typewriter to determine the line-space-stroke. For holding the U-shaped piece in its different positions, the handle 60 portion thereof, which also bears on the platen-axle, has a notched edge into the notches of which is pressed the roll of a spring-pressed detent-arm. The number of 65 steps on the stop-sector and the corresponding notches, as shown herein, provide for

multiples of one and one-quarter, one and one-half, two, and three times a single line-space-unit.

A line-space-handle or lever preferably mounted upon the frame of the letter-feeding typewriter-carriage may be operatively connected to the aforesaid slide in a manner to permit case-shifting. In the herein-shown form of the invention, the line-space-lever actuates a reciprocatory slide similar to the usual Underwood reciprocatory line-space-slide, which as will be shown it replaces. Said latter slide is connected to the aforementioned sector-operating slide by means of an intermediate pinion, each slide being for this purpose provided with rack-teeth to engage said pinion. Like in the usual Underwood typewriter, there is, during case-shifting, a relative up and down movement between an arm of the line-space-lever and the end of the aforesaid slide which said lever actuates.

The sector-operating slide may be mounted in a fixture or plate which may be fastened to the upper surface of the end-member of the usual Underwood platen-frame, said plate having downwardly-bent portions in which opposite ends of the sector-operating slide have their bearings. Another downwardly-bent portion carries a fulcrum for the aforementioned sector and may have an extension bent inwardly toward the aforesaid platen-frame-end-member to be secured thereto for the purpose of bracing and supporting said plate. Suitable indicating means may be provided, as will be shown, to serve as an indication of the extent to which the line-space-unit is adjusted.

The aforesaid pawl and ratchet-wheel, forming the clutch-mechanism, are normally disconnected so that the platen may be rotated by hand by means of either the aforesaid cylindrical shell or platen-knob, independently of said clutch-mechanism. The pawl is spring-pressed and is normally held disengaged from the ratchet-wheel by novel means which also serve to cause the pawl to engage the ratchet-wheel or to be disengaged therefrom at the beginning and end respectively of a line-space-stroke of the pawl-arm.

The mechanism is so arranged that, irrespective of the extent to which the platen is line-spaced, the pawl-arm at the end of its line-spacing stroke always reaches the same position. This is done so that the pawl may react against a fixed stop at the end of the line-space-stroke to prevent overthrow of the platen. As the pawl encounters said stop and reacts against the same, the teeth of the pawl and ratchet are caused to be interlocked and thus prevent said overthrow. A brake is applied to the ratchet-wheel end of the aforesaid train of epicyclic gearing, said brake serving to facilitate the oper-

ation of the mechanism, and particularly serving to facilitate the disengagement of the pawl from said ratchet-wheel at the beginning of a return stroke of the pawl-arm.

This invention is in the nature of an improvement upon the mechanism disclosed in my earlier filed application, Serial No. 137,948, filed September 27, 1926. The claims in this case are limited to features that are not disclosed in said application 137,948.

10 Other features and advantages will hereinafter appear.

In the accompanying drawings,

15 Figures 1 and 2 are a top plan view and a side elevational view, respectively, of the mechanism of the invention. Said figures illustrate particularly the compact and neat-appearing arrangement of said mechanism.

20 Figure 3 is a top plan view, showing parts of the mechanism in detail and the relative arrangement of said parts.

25 Figure 4 is a side elevational view, illustrating the slide carrying the shiftable pin and the manner in which said slide by means of said shiftable pin is connected to a circular rack-member. There are also shown an oscillatory pawl-carrying arm which is actuated by said circular rack-member and the means for controlling the pawl on said 30 arm with respect to the ratchet-wheel which said pawl engages during line-spacing.

35 Figures 5 and 6 are a top plan view and a side elevational view, respectively, showing details of the slide which carries the aforesaid shiftable pin, and also showing in detail means whereby said pin may be shifted at will. Said Figures 5 and 6 also show the adjustable stopping means whereby the movement of said slide is limited for 40 selectively determining single line-spacing or multiples of said single spacing.

45 Figure 7 is a side elevational view, illustrating how a portion of the slide stop member may be provided with detent-notches and a spring-pressed arm co-operating with said notches to hold said member in any selected position.

50 Figure 8 is a front elevational view, illustrating the arrangement of the parts as seen in said view.

55 Figure 9 includes a side elevation, showing the pawl engaged with the ratchet-wheel for line-spacing and also showing the relative position of the pawl-controlling annular shaped piece when said pawl is so engaged. Said Figure 9 also indicates the epicyclic train of gearing as viewed endwise of the platen-axle. A plan view of the pawl is also 60 included in said Figure 9 to illustrate that the annular-shaped pawl-controlling piece is offset to engage a projection of said pawl. There is also indicated in said Figure 9 a counter-weight with which the pawl may be 65 provided to counterbalance the centrifugal

force which tends to disengage the pawl and ratchet-wheel during line-spacing.

70 Figure 10 shows a side-elevational view of the reciprocatory slide that replaces the usual Underwood reciprocatory line-space slide. There is also included in said Figure 10 a front-end view of the platen-frame end member to illustrate the opening in said front end through which said reciprocatory slide with its rack may be readily inserted.

75 Figure 11 shows means whereby the worm on the reciprocatory slide may be secured against displacement.

80 Figure 12 is a sectional perspective view of the improved line-spacing mechanism in one form.

85 The invention is herein shown as applied to line-space the platen 15 of the well-known Underwood typewriter. There is shown only a fragmentary portion of said platen which is keyed to a platen-axle 16 journaled in the usual platen-frame, of which only the left end-member 17 is shown. Said platen-frame and its platen are movable up and down, as usual, for case-shifting, and are carried by the usual Underwood letter-feeding carriage, of which only a fragmentary portion of the carriage-frame 18 is indicated in the drawings, said portion having mounted thereon the usual Underwood line-space-lever 19. 90 The extent of the swing of said lever is limited by the usual stops 20.

95 In providing for simplicity of arrangement and compactness of the variable line-spacing means connecting said lever and platen, there is employed a reciprocatory slide 21, mounted for movement transversely of the platen-axle in a fixture generally indicated by the number 22. Said fixture, as shown herein, includes a flat plate 23, which may be secured to the top surface of the aforesaid platen-frame end-member 17 by 100 screws 24, and for retaining the slide 21, said fixture has portions 25 which may be bent downwardly from said plate 23 to serve as bearings for opposite ends of said slide 21.

105 It will be obvious that for operating said slide to and fro to effect line-spacing, direct connection may be made to the line-space-lever 19 if the direction in which the arm 26 of said lever extends is reversed. Preferably, however, in order to avoid changing the design of the line-space-lever, another reciprocatory slide 27, which may 110 conveniently replace the usual Underwood line-space-slide, is used, and for transmitting the movement of the line-space-lever 19 and said other slide 27 to the slide 21, said slides are provided with racks 28 and 29, respectively, formed in bent-over portions 115 of said slides, as best shown in Figures 3 and 8. A pinion 30, meshing with said racks, connects the slides and may be conveniently mounted on a stud 31 projecting from the under surface of the fixture-plate 23. The 120 125 130

slide 27 has a bent-over end 32, against which the arm 26 of the line-space-lever reacts. Said end 32 is of sufficient depth so that the line-space-lever-arm 26 may engage 5 said end irrespective of whether the platen is in upper or lower case position, there being the usual relative up and down displacement of said end 32 and arm 26 during case-shifting.

10 A member 34, forming a circular rack 35, is provided, and by means, which will presently be explained, any given movement of the slide 21 results in a selectively variable movement of said member 34, and consequently selectively and minutely variable line-spacing, said movement being transmitted to the platen-axle to effect said line-spacing of the platen. On account of said movement being variable and as it is to be 20 effective in one direction only to line-space the platen, its transmission to the platen-axle is best effected by means including a clutch, of which any one of various forms may be employed. In the herein shown form 25 of the invention, said clutch includes a ratchet-wheel 36 and an oscillatory element which may be an arm 37, carrying a spring-pressed pawl 38. In order that the pawl may drive the ratchet-wheel positively and 30 control the same, both wheel and pawl are provided with teeth 36^a and 38^a, respectively, the teeth of the wheel encircling its circumference. The arm 37 derives its oscillatory movement from the member 34 by means 35 of the rack-teeth, 35, which engage and drive a pinion 39, forming part of said arm 37. On account of the variable extent of movement of said arm 37 to effect variable extents of line-spacing, there is usually an aliquant relation of the pitch of the ratchet-wheel-teeth to the arm movement which effects said line-spacing, from which it results that the teeth of the pawl 38 will not 40 always directly engage the teeth of the ratchet-wheel. Said arm will, therefore, usually have an idle movement or lost motion relative to the ratchet-wheel before said teeth which are formed, as shown, may engage. In order that the effect of said idle 45 movement upon uniformity of line-spacing may be negligible, the pitch of the teeth is made very fine, say not over 1/32 of an inch from tooth to tooth, and the arm 37 is given a movement which is substantially greater 50 than the line-spacing movement of the platen effected thereby. In this manner the idle movement of the arm 37, which never exceeds one tooth-space, is a very small part of said large movement of the arm 37, and, 55 therefore, its effect upon uniformity of line-spacing is practically negligible.

The movement or extent of rotation of the arm 37 and ratchet-wheel 36 being substantially larger than the line-space-movement 60 of the platen which is to result therefrom,

there is employed a train of reducing gearing between said ratchet wheel and the platen, said train being epicyclic in character so that it may be entirely supported upon and concentric with the platen-axle, thereby 70 conducting to neatness of appearance and compactness. Another advantage of the use of an epicyclic train over the worm and worm-wheel-train heretofore used in similar mechanisms is that the back-lash and wear attending the use of a worm and worm-wheel is avoided. The epicyclic train consists of a driving gear 40 located loosely upon the platen-axle and rigidly connected to the ratchet-wheel 36 by means of an indeterminate 75 flange, spider, or web 41. An arm 42 of the epicyclic train is keyed to the platen-axle and carries at its outer end a pinion 43 which meshes with the gear 40 on the platen-axle. Alongside of said pinion 43 and rigidly connected thereto is a second pinion 44, both pinions rotating upon a stud 42^a carried by said arm 42. Said second pinion 44 meshes with an annular gear 45 which constitutes the fixed member of said train. In order that said annular gear may be supported concentrically with the platen-axle, it is provided with a web 46 having a central hub 47 bearing upon said platen-axle. To fix the annular gear 45 against rotation, 95 it is anchored to the fixture 22 by means of a strap 48, one end of which may be secured to the web 46 of said annular gear, the other end of the strap being secured to a downwardly-bent portion 49 of the fixture-plate 100 23.

The downwardly-bent fixture-portion 49 of the fixture 22 also carries a pivot 50 upon which the circular rack-member 34 swings, said circular rack-member having a hub 51 105 to afford an extent of bearing which is sufficient to prevent wabbling. The downwardly-bent portion 49 may be braced by means of an extension 52 thereof which is bent inwardly toward the end-member 17 of the platen-frame, the end of the extension being bent parallel to said frame so that it may be secured by a screw 54 to a stud 53 projecting from said end-member (see Figure 3).

The diameters of the several gears and pinions constituting the epicyclic train are so proportioned that the maximum rotation of the ratchet-wheel 36 and gear 40 produces the maximum desired line-space-rotation of the platen. In order that a stop against which the pawl 38 may react at the end of the line-space-stroke may be conveniently provided, and which stop will be described later on, the maximum rotation of the ratchet-wheel is restricted to say 5% of a whole 115 revolution. For this maximum rotation of the ratchet-wheel 36, it is arranged that the circular rack-member 34 rotates through say 1/8 of a complete revolution, the pitch-diameters of the rack 35 and pawl-arm-pinion 120 125

39 being proportioned accordingly. The several gears and pinions of the epicyclic train may be so proportioned that the extent of maximum line-space-rotation resulting from the maximum rotation of the line-space-wheel is $\frac{2}{3}$ of an inch. It will be understood that the invention is not limited to the particular figures herein mentioned as descriptive of the extent of movement of 5 the various parts of the mechanism, said figures being merely illustrative. Such being the case, it may be further said in a descriptive sense that the slides 21 and 27 have a reciprocatory movement for maximum or 10 triple-spacing of say $\frac{1}{2}$ inch. Whatever the given movement of said slide 21 may be, and in order that such given movement may impart a variable movement to the circular rack-member 34, there is shiftably mounted upon 15 said slide 21 a pin 56 which, by means of a sliding block 57 surrounding the end of said pin, engages a slot 58 formed in said circular rack-member 34. Said pin 56 extends from the inner side of the sector to 20 and beyond the outer side, which is adjacent said circular rack-member, through a slot 59, which is formed in said slide, said slot 59 serving not only to retain said pin endwise of the slide 21, but also to guide said 25 pin toward or away from the pivot 50 of the circular rack-member 34. As said pin 56 is moved toward or away from said pivot, there will be a corresponding increase or decrease of the movement of the circular rack- 30 member 34 for a given movement of said slide 21. Furthermore, the slot 59 and the consequent direction in which the pin 56 may be shifted, extend perpendicularly to the direction of movement of said slide 21. 35 In the drawings, the slide is shown at one extreme position which is also its normal position in its maximum range of movement. At the opposite extreme position of said maximum movement, the pin 56 in slot 59 40 would be on the other side of the pivot 50, as shown in Figure 4 by the dot-and-dash lines. A perpendicular from the center of said pivot 50 to a line joining said extreme positions would bisect said line; thus for 45 maximum movement of the slide 21, the pin 56 has an equilateral movement on either side of the pivot 50, as shown in said Figure 4. Such equilateral movement occurs irrespective of the position 50 of the pin 56 along the slot 59. The maximum movement of the slide 21 is usually associated with triple-spacing. For single and double spacing, the extent of movement of the slide 21 is proportioned according 55ingly and by means which will be described later. It will be evident that by having the pin 56 move equilaterally on either side of the pivot 50 for a maximum movement of the slide 21, there will be, irrespective of 60 the position of the pin 56, a more near ap-

proach to uniformity in the ratio of maximum line-spacing of the platen to sub-multiples of said spacing, as, for example, single or double spacing, than has heretofore been obtained.

A feature of the invention is the novel means whereby the pin 56 may be shifted upon the slide 21 to change its position with respect to the circular rack-pivot 50. Said means include a worm-wheel-segment or its equivalent, forming a pin-shifting segment 61 whose teeth are concentric with said pin 56. Said segment carries said pin 56 and has a portion 61^a extending toward a stud 62 projecting from the inner surface of the slide 21.

Said segment-portion 61^a has a slot 63 which embraces said stud, which thus serves as what may be called a fulcrum around which the pin-shifting segment 61 may be swung or shifted to raise or lower the pin 56 carried thereby. It has already been explained that the pin 56 is retained endwise of the slide 21 by the sides of the slot 59. To retain the pin-shifting segment 61 and its pin 56 upon the slide, said pin has a broad shoulder 64, which, with the opposite surface of the pin-shifting segment 61, embrace the side surfaces of the slide 21. To secure the pin against shake or play, the fit between the side surfaces of the slide 21 and the embracing surfaces of the pin-shifting segment 61 and pin-shoulder 64 may be made close enough to prevent said play. Said fit may be so close that there may be a slight bind between said surfaces when the parts are assembled. The pin 56 may be secured to the pin-shifting segment 61 by means of a nut 65 threaded upon a shouldered shank of the pin 56. The pin 56 is shifted along the slot 59 by turning the pin-shifting segment about the axis of said pin 56, said turning movement reacting upon the sides of the slot 59 and upon the stud 62, and causing the pin 56 to move along said slot 59. For shifting the pin 56 in this manner the pin-shifting segment 61 is turned by means of a worm 66 meshing therewith. Said worm is revolvably mounted upon the slide 21 and is keyed to a short spindle 67 carrying at its upper end a finger-knob 68 whereby the worm may be easily manipulated and rotated to effect shifting of the pin 56. Said spindle 67 is journaled in bearings 69 forming part of the slide 21, said bearings preferably retaining the worm in such position with respect to said slide that an opening 70 in the slide is required to clear the worm.

The slide with its pin-shifting segment 61, worm 66, finger-knob 68, etc., form a unit which moves to and fro for line-spacing. It is therefore desirable that all of the parts constituting said unit be made as light as possible. For example, several panel openings, not shown, may be made in the slide

21; the pin-shifting segment 61 may also be of skeletonized structure and the knob 68 may be of hollow formation. Said finger-knob 68, in order to be easy of access, projects above the fixture-plate 23 which has a clearance-opening 71 to clear the spindle 67 as the slide moves to and fro.

Indicating means, which serve as an index of the position of the pin 56 and consequently of the extent of line-spacing corresponding to said position, may be provided in various forms. The preferred form of such indicating means includes a flat rod 73 whose lower end fits loosely over the pin 56, the rod being between the circular rack-member 34 and the flange forming the shoulder 64 of the pin 56, as best shown in Figures 3 and 6. The upper end-portion of said rod may be guided edgewise in a shallow and preferably open slot formed in a bent-over portion 74 of the upper edge of the slide 21. The rod may be provided with scale-markings 75 which are clearly visible above the top-surface of the fixture-plate 23 above which said rod projects through a slot 76 in said plate. The upper edge of said slot adjacent the scale-markings 75 co-operates with said markings in indexing the position of the rod and consequently of the pin 56. Said slot 76 also retains the rod facewise and is extended sufficiently along the plate 23 in accordance with the endwise movement of the slide 21 upon which said rod is mounted.

Novel means are provided to limit the endwise movement of the slide 21, and said means may be considered as providing for single line-spacing or several predetermined multiples of said single line-spacing, the extent of said single spacing or its multiples being in turn selectively determinable and minutely variable by turning the knob 68 of the aforementioned means for shifting the pin 56.

The means for limiting the movement of the slide 21 include a U-shaped piece rotatable about the platen-axle, said U-shaped piece having sides 78 and 79 which bear upon said platen-axle and are connected by a tie 80 forming part of said piece. The side 78 of said U-shaped piece has a stepped edge forming several slide-stops 77 located at different distances radially from the platen-axle, said distances depending upon the limit of slide-movement to be established by said stops. In the illustrated form of the invention, the number of stops and said distances thereof limit the slide to movements corresponding to single line-spaces or multiples of $1\frac{1}{4}$, $1\frac{1}{2}$, 2, and 3 times the extent of single spacing. The arrows in Figure 3 indicate the direction of movement of the slides during line-spacing strokes. The slide 21 is normally drawn against one of the stops 77 by means of a spring 81,

the slide being provided with a bent-over projection 82 which reacts against said stops. The U-shaped piece is rotatable about the platen-axle to bring the desired stop into position. For holding the U-shaped piece in its several positions according to the stops selected, the side 79 on said piece has formed upon its outer edge detent-notches 83 which are so disposed that a roll 84 of a detent-arm 85 when pressed into one of said notches holds the U-shaped piece in one of its slide-stopping positions. The outer edges of the extreme notches may be extended radially to react against detent-roll 84 in such manner that movement of the U-shaped stop-piece beyond its normal limits is prevented. Said detent-arm 85 is spring-pressed and the notches which said arm engages are so disposed that there may be used the regular detent-arm which is used in conjunction with the usual Underwood line-space-wheel, said wheel being omitted in the present invention.

In order that the U-shaped stop-piece may be easily manipulated, there extends from the side 79 of said piece a handle 87, which projects through an opening 86 in the side of the platen-frame end-member 17 so that its upper portion, which carries a finger-knob 88 may be in substantially the same position heretofore occupied by the usual Underwood finger-piece that is shiftable for selecting a single line-space-unit or multiples of said unit. As shown in Figure 6, the U-shaped stop-piece is set for triple-spacing. The dotted circles 88^a indicate the several positions of the knob 88 corresponding to the several stop-positions of the U-shaped stop-piece. The side 78 of said U-shaped stop-piece may be conveniently disposed between the circular rack-member 34 and the slide 21, as best shown in Figure 8.

As already stated, the pawl 38 is spring-pressed toward the ratchet-wheel 36. Said pawl is to be held normally disengaged from said ratchet-wheel in order to permit independent movement of the platen 15 by means of the usual platen-knob 90 or a rotatable cylindrical shell 91 which surrounds the flange, spider or web 41, and being rigidly connected thereto, and, hence, connected to the ratchet-wheel 36 and the gear 40, said shell thus having the same ratio of movement to the platen-movement that the ratchet-wheel 36 and gear 40 have. As said ratio is a large one, the cylindrical shell 91 serves to slowly rotate the platen 15 and thereby effect fine adjustment of any portion of a work-sheet on said platen to the printing line of the typewriter. Said cylindrical shell also serves to substantially cover the epicyclic train of gearing and its associated ratchet-wheel 36 and driving pawl 38, thus conducing to the neat appearance of the 130

mechanism and also serving as a guard for said train and its adjacent parts.

For keeping the driving pawl 38 normally disengaged from the ratchet-wheel 36, and also for causing said pawl and ratchet-wheel to be engaged at the beginning of a line-space stroke of the oscillatory member or arm 37, and also for causing said pawl and ratchet-wheel to be disengaged at the beginning of the return stroke of said arm, there is provided a revoluble annular-shaped piece 92 which is concentric with the platen-axle and has a radial projection 93 extending toward said pawl and having an inclined edge 94. A stud 95, projecting from the side of said pawl, reacts upon said edge 94. It will be seen that a relative rotary movement of said pawl and edge 94 about the platen-axle will cause the stud 95 of said pawl to ride up or down said slide, which in turn causes the pawl to be disengaged or engaged. In order to obtain this relative rotary movement of the pawl 38 and edge 94, the annular piece 92 is frictionally held against rotation and is connected to the pawl-arm 37 by a lost-motion connection in such manner that an initial movement of said arm in either direction will cause said relative rotary movement. The pawl-arm 30 has accordingly a stud 97, which may react either against the side of the aforesaid projection 93 of the annular piece 92 or the side of a similar but shorter projection 98, which also extends from said annular piece, said 35 sides being spaced far enough to afford the required extent of the aforesaid relative rotary movement. As shown in Figure 8, the annular-shaped piece 92 is held in a groove concentric with the platen-axle, said 40 groove, as shown in Figure 8, being formed between the side of a circular-shaped portion 99 of the fixture 22 and a stepped side of a disk or washer 101. The required friction, which retards rotation of the annular piece 45 92, may be obtained by making said piece of resilient material and warping it out of shape before it is inserted in said groove. The aforesaid disk or washer 101 has an opposite stepped side which with another 50 washer 102 forms a second groove in which another annular-shaped piece 103 is retained and frictionally held against rotation. Said other annular-shaped piece 103 may engage the ratchet-wheel by a tongue-and-slot connection 96 and said piece 103 thus serves as a brake upon the ratchet-wheel-end of the epicyclic train of gearing to facilitate the disengagement of the pawl and ratchet-wheel at the beginning of a return stroke 55 of the pawl-arm 37. Said brake also prevents idle floating movement of the ratchet-wheel-end of said train. The circular-shaped portion 99 of the fixture 22 and the washers 101 and 102 may be clamped together by a suitable number of screws 104

and may conveniently serve as an out-board bearing for the platen-axle. Said portion 99 and washers 101 and 102 thus form circular portions extended from the fixture 22 and connected thereto by a spur 100. As shown in Figure 8, a hub 105 of the pawl-arm 37 may extend into said bearing into the line of reaction of the over-hanging pawl 38.

As previously mentioned, the pawl-arm 37 always moves to the same position irrespective of the extent of line-spacing in order to provide for a fixed stop against which said pawl may react. As shown in Figures 3, 4 and 9, said stop is in the form of a projection 106 bent endwise with respect to the platen-axle from the spur 100 of the fixture 22 and into the path of the end of said pawl. Said projection may have a beveled edge 108 against which a beveled edge 107 of the pawl may wedge at the end of a line-space-stroke and thus cause the teeth of the pawl and ratchet-wheel to interlock and thereby prevent overthrow of the patent. The teeth of the pawl and ratchet-wheel being of very fine pitch, as already mentioned, it is desirable that the pawl have numerous teeth, as shown in Figures 4 and 9, in order that the teeth of the pawl will hold sufficiently to prevent said overthrow.

Figure 9 shows the pawl 38 in engagement with the ratchet-wheel 36, the pawl and ratchet-wheel being shown in side elevation from which there is projected a plan view of the pawl to illustrate the stud 95 thereon. It is desirable that the extent to which said stud projects from the side of the pawl be limited sufficiently to insure that the end of said stud will clear the side of the spur 100 of the fixture 22 as said pawl approaches the stop projection 106. To accommodate the limited length of said stud, the projection 93 of the annular-shaped pawl-controlling piece 92 is offset, as shown, to bring the beveled edge 94 of said projection under said stud 95.

In order that the slide 21 may be inserted in the fixture 22, the rear one of the downwardly-bent portions 25 of said fixture is formed as indicated in Figure 6. Said rear portion 25 has a T-shaped slot 109, which forms a bearing for the rear end of the slide. Said slot is T-shaped, that is to say, it is partly open at its outer side, so that the slide 21 may be inserted sidewise. Said slide, when it is to be inserted or removed, is moved rearwardly sufficiently, so that a notch 110 clears the spur 111 of said slot, while, at the same time, the front end 112 of said slide is free of the front downwardly-bent projection 25 of the fixture 22. The notch 110 is made sufficiently deep, so that the slide 21 may be lowered enough to facilitate the insertion of the upper end of the indicating rod 73 into its slot 76 in the plate 23 of the fixture 22. Said rear downwardly-bent portion 25 also has a lug 116 to which one end of the slide 130

spring 81 may be anchored, the other end of said spring being attached to a stud 117 projecting from the side of the slide. The front downwardly-bent portion 25, which serves as a bearing for the front end of the slide 21, may have a slot therein similar to the illustrated slot in the rear downwardly-bent portion 25, that is to say, a T-shaped slot; or the slot in said front portion 25 may be closed. The T-shaped slot 109 in the rear portion 25 has a clearance notch 118 that clears the stud 62 on the slide as said slide is moved rearwardly for its insertion into the fixture 22 or its removal therefrom. The finger-knob 68 is to be removed when the slide 21 is inserted or removed from the fixture 22.

The spindle 67 to which said knob is attached and the pin-shifting segment 61 are also to be removed to facilitate the insertion or removal of the slide 21. The upper bearing 69 for the spindle 67 is formed, as shown, by a projection bent sidewise from the upper edge of said slide. The lower bearing 69 for said spindle may be formed in a block, which may be attached to the side of the slide 21, as indicated in the drawings. The upper end of the worm 66 may have a hub 119, through which a pin may be driven to key said worm to the spindle 67. A pin may also be driven through the lower end portion of the finger-knob 68 to key said knob to said spindle. The worm 66 is retained endwise between the bearing 69, the upper end of the hub 119 bearing against the under surface of the upper bearing 69, while the lower end of the worm bears upon the block forming the lower bearing 69. The upper and lower edges of the opening 70 in the slide 21 may clear the upper and lower ends of the worm 66.

In Figure 10 a side view of the slide 27 is shown in detail. Said slide replaces the usual Underwood line-space slide, and is retained and guided in the same bearings 113 and 114, which serve to retain and guide said Underwood line-space slide, said bearings being attached to and forming part of the platen-frame end member 17. In said Figure 10 there is also shown a front-end view of a front end 17^a of said end member 17 to illustrate the usual opening 115, which also serves to clear the rack 28 of said slide 27 as said slide is inserted endwise into its bearings 113 and 114.

To indicate the setting of the U-shaped stop-piece that limits the movement of the slide 21, there may be provided on the upper surface of the plate 23 and the fixture 22 markings 120, said markings being placed upon said surface opposite the several positions which the knob 88 assumes, in accordance with the several positions of the U-shaped stop-piece. As shown in Figure 1, said markings indicate single line-spacing

or multiples of one and one-quarter, one and one half, two and three times said single line-spacing. For triple spacing the end 32 of the slide 27 will be against the end of the arm 26 of the line-space lever 19. For lesser extents of slide movement the end 32 of said slide will normally be in a position as indicated, for example, by the dot-and-dash outline of said end 32 in Figure 1. Whatever the position of the end 32 may be, it is preferable that the line-space lever normally bear against the left line-space lever-stop 20, and, for this purpose, a spring 121 may be provided to normally urge said lever against said left stop, said spring being a torsion spring wound around the hub of the line-space lever, one end of said spring reacting against said lever and the other end reacting against a suitable portion of the carriage-frame 18, as shown in Figures 1 and 2.

The ratchet-wheel 36, the gear 40 and the cylindrical shell 91 of the epicyclic train are shown herein as being formed in one piece with the web, flange or spider 41. It will be understood that these parts may be separate members assembled in any suitable manner to form the composite member herein shown, and which includes said parts. In a similar manner the annular gear 45 and the part forming the web 46 and 47 of said annular gear may be separate parts assembled in a suitable manner to form the composite member shown. The member formed by the ratchet-wheel 36, gear 40, cylindrical shell 91 and web 41, having a comparatively high velocity of rotation during line-spacing, is to be made as light as possible. The rack-forming member 34 may also have panel-openings, not shown, whereby surplus material is eliminated to secure lightness, it being understood that lightness in all the moving parts is desired on account of the usual sudden starting and stopping of the movements of said parts in line-spacing.

As already mentioned, the pawl 38 is spring pressed so that it is urged into engagement with the ratchet-wheel 36. There is accordingly provided a torsion spring 122, Figure 8. Said spring 122 may be wound around a hub-portion 38^b of said pawl, one end of which may be threaded into a hole drilled into the side of the pawl, the other end being threaded into a similar hole drilled into the flange of stud 33, upon which said pawl is pivoted. The pawl is cut away to said hub-portion 38^b, as indicated at 123, Figure 9, the pawl being thus cut away to clear the circumference of the ratchet-wheel. As the pawl revolves at a comparatively high velocity while in engagement with the ratchet-wheel, there is developed considerable centrifugal force, which may be balanced by the spring 122. In order to make said spring as light as possible, however,

there may be provided, if desired, a counter-weight 123^a, which may be attached to the pawl, as shown in Figure 9. As shown in Figure 9, which includes a plan view of the pawl, the counterweight 123^a is offset from the pawl; this being done in order that the counterweight may not interfere with the spur 100 or the pawl-stopping projection 106, the counterweight being behind the pawl-arm 37 and on the inner side of the spur 100 of the fixture 22.

Means may be provided whereby the worm 66 on the slide 21 may be secured against displacement after said worm has been rotated to adjust the position of the pin 56. A preferred and simple form of such means consists of a detent 124 made of thin spring material and formed as indicated in Figure 11. The lower portion of said detent may be secured against the side of the detent-slide 21 by rivets 125. Due to the resiliency of said detent 124 the upper end thereof is spring pressed against the straight knurl 126 of the finger-knob 68, said upper end of the detent having a V-shaped formation 127, which is pressed into the flutes of said knurl, thereby to avoid abnormal displacement of the worm 66. It will be understood that preferably the pressure of said detent 124 is not sufficient to prevent rotating the finger-knob 68 by hand when it is desired to shift the position of the pin 56. The opening 71 in the top plate 23 of the fixture 22 may be widened sufficiently to clear said detent 124 as it projects therethrough; or said detent may be formed to clear said opening.

Variations may be resorted to within the scope of the invention, and portions of the improvements may be used without others.

Having thus described my invention, I claim:

1. The combination with a revoluble typewriter-platen and a line-space lever, of a reciprocatory slide operable by said lever, a member forming a circular rack, a pin shiftably mounted on said slide and engaging said member for joint reciprocatory movement of said slide and member, means upon said slide for shifting said pin at will to change its position upon said slide relative to the fulcrum of said member thereby to vary the movement of said member for any given movement of said slide, and means driven by said rack whereby the movement of said member in one direction is translated into line-space rotation of the platen.

2. The combination with a revoluble typewriter-platen and a line-space lever, of a reciprocatory slide mounted for rectilinear movement at right angles to the platen-axis and operable by said lever, a member forming a circular rack, said member being disposed so that it swings in a direction parallel to the direction of movement of said slide,

a shiftable pin projecting from said slide and engaging said member for joint reciprocatory movement of said slide and member, means upon said slide for shifting said pin at will to change its position upon said slide relative to the fulcrum of said member thereby to vary the movement of said member for any given movement of said slide, and means driven by said rack whereby the movement of said member in one direction is translated into line-space rotation of the platen.

3. The combination with a revoluble typewriter-platen and a line-space lever, of a reciprocatory slide operable by said lever, a member forming a circular rack, a pin shiftably mounted on said slide and engaging said member for joint reciprocatory movement of said slide and member, means for shifting said pin at will to change its position upon said slide relative to the fulcrum of said member thereby to vary the movement of said member for any given movement of said slide, and means driven by said rack whereby the movement of said member in one direction is translated into line-space rotation of the platen.

4. The combination with a revoluble typewriter-platen and a line-space lever, of a reciprocatory slide operable by said lever, a member forming a circular rack, a pin shiftably mounted on said slide and engaging said member for joint reciprocatory movement of said slide and member, means for shifting said pin at will to change its position upon said slide relative to the fulcrum of said member thereby to vary the movement of said member for any given movement of said slide, said member having a slot with a slide therein, said last-mentioned slide fitting over said pin, and said slot being disposed in a direction corresponding to the movement of said pin toward or away from the fulcrum of said member, and means driven by said rack whereby the movement of said member in one direction is translated into line-space rotation of the platen.

5. In a line-spacing mechanism for a revoluble typewriter-platen, the combination of a reciprocatory slide operable to line-space said platen, a member forming a circular rack, a pin shiftably mounted on said slide and connecting said slide and member for joint reciprocatory movement, said slide having means for shifting said pin at will to change its position upon said slide relative to the fulcrum of said member thereby to vary the movement of said member for any given movement of said slide, and means driven by said rack whereby the movement of said member in one direction is translated into line-space rotation of the platen.

6. A variable line-spacing mechanism for a revoluble typewriter-platen, including a

reciprocatory slide operable to line-space said platen, a member forming a circular rack swingable about a fulcrum whose axis extends transversely of the direction of movement of said slide, a pin shiftably mounted on said slide and connecting said slide and member for joint reciprocatory movement, said slide having means for shifting said pin at will to change its position upon said slide relative to the fulcrum of said member thereby to vary the movement of said member for any given movement of said slide, said means including a worm-wheel segment carrying the shiftable pin, a stud in said slide about which said segment may be shifted to shift said pin, said means also including a manually-operable worm mounted on said slide for shifting said segment and thereby said pin, and means driven by said rack whereby the movement of said member in one direction is translated into line-space rotation of the platen.

7. A variable line-spacing mechanism for a revolute typewriter-platen, including a reciprocatory slide operable to line-space said platen, a member forming a circular rack swingable about a fulcrum whose axis extends transversely of the direction of movement of said slide, a pin shiftably mounted on said slide and connecting said slide and member for joint reciprocatory movement, said slide having means for shifting said pin at will to change its position upon said slide relative to the fulcrum of said member thereby to vary the movement of said member for any given movement of said slide, said means including a worm-wheel segment carrying the shiftable pin, a stud in said slide about which said segment may be shifted to shift said pin, said means also including a manually-operable worm mounted on said slide for shifting said segment and thereby said pin, means driven by said rack whereby the movement of said member in one direction is translated into line-space rotation of the platen, and indicating means serving as an index of the position of said pin and consequently of the extent of the corresponding line-space rotation of said platen, the extent of said latter rotation being variable by reason of the variable movement of said member.

8. A variable line-spacing mechanism for a revolute typewriter-platen, including a reciprocatory slide operable to line-space said platen, a member forming a circular rack swingable about a fulcrum whose axis extends transversely of the direction of movement of said slide, a pin shiftably mounted on said slide and shiftably guided by a rectilinear slot in said slide, said slot extending perpendicularly to the direction of movement of said slide, said pin serving to connect said slide and member for joint reciprocatory movement, means associated

with said pin and slide for shifting said pin at will to change its position relative to the fulcrum of said member thereby to vary the movement of said member for any given movement of said slide, said means including a worm-wheel segment carrying the shiftable pin and having a tooth-arc concentric with said pin, a stud in said slide about which said segment, at a point opposite the teeth thereof and on the diametrically-opposite side of said pin, may be shifted, said means also including a manually-operable worm mounted in said slide and engaging said segment for shifting the same and thereby said pin, and means driven by said rack whereby movement of said member in one direction is translated into line-space rotation of the platen, said rotation being variable by reason of the variable movement of said member.

9. The combination with a revolute typewriter-platen keyed to an axle, and a line-space lever, of a revolute member loosely mounted on said axle, means including an oscillatory element having clutch-teeth co-operating with similar teeth that are associated with said member whereby the movement of said lever in a line-spacing direction causes rotation of said member, and an epicyclic train of gearing centered upon and supported by the platen-axle and connecting said member to said axle for translating a large rotary movement of said member into platen-rotation of line-spacing extent, said means being further devised so that the rotation of said element and member is of a substantially greater extent than the resultant line-space rotation of said platen thereby to minimize the herein described effect of the aliquant relation of the pitch of said teeth to the movement of said element and member.

10. The combination with a revolute typewriter-platen keyed to an axle, and a line-space lever, of a revolute member loosely mounted on said axle, an oscillatory element also loosely mounted on said axle, means having clutch-teeth co-operating with similar teeth associated with said member for enabling said oscillatory element in one direction of its movement to rotate said member, means whereby the line-space lever may drive said oscillatory element through a rotary movement, and an epicyclic train of gearing centered upon and supported by the platen-axle and connecting said member to said axle for translating a large rotary movement of said member into platen-rotation of line-spacing extent, the means driving said oscillatory element being devised so that the rotary movement of said element and member is of substantially greater extent than the line-space rotation of said platen, thereby to minimize the herein-described effect of the aliquant relation of the

pitch of said teeth to the movement of said element and member.

11. The combination with a revolute typewriter-platen keyed to an axle, and a line-space lever, of a revolute member loosely mounted on said axle, an oscillatory element also loosely mounted on said axle, means having clutch-teeth co-operating with similar teeth associated with said member for enabling said oscillatory element in one direction of its movement to rotate said member, means whereby the line-space lever may drive said oscillatory element through a rotary movement, and an epicyclic train of gearing centered upon and supported by the platen-axle and connecting said member to said axle for translating a large rotary movement of said member into platen-rotation of line-spacing extent, the means driving said oscillatory element being devised so that the rotary movement of said element and member is of substantially greater extent than the line-space rotation of said platen, thereby to minimize the herein-described effect of the aliquant relation of the pitch of said teeth to the movement of said element and member, said train including an annular gear concentric with the platen-axle and fixed against rotation, an arm keyed to said axle and carrying a pinion meshing with said annular gear, a second pinion rigidly connected to and alongside of the first pinion and concentric therewith, and a gear meshing with said second pinion, said last-mentioned gear mounted upon and revolute upon said axle and constituting the driver of said train during line-spacing.

12. In a line-spacing mechanism for a revolute typewriter-platen keyed to an axle, the combination with a reciprocatory member operable to line-space the platen, of means including a clutch and an epicyclic train of gearing, whereby the movement of said member in one direction causes the platen to be line-spaced, said train including an annular gear concentric with said axle and fixed against rotation, an arm keyed to said axle and carrying a pinion meshing with said annular gear, a second pinion rigidly connected to and alongside of the first pinion and concentric therewith, and a gear meshing with said second pinion and loosely mounted upon said platen-axle, said last-mentioned gear constituting the driver of said train, the driven portion of said clutch being connected to the driver-gear, the driving portion of said clutch being revolute about said axle and operatively connected to said reciprocatory member, and a cylindrical shell surrounding and substantially covering said train of gearing and clutch.

13. In a line-spacing mechanism for a revolute typewriter-platen keyed to an axle, the combination with a reciprocatory mem-

ber operable to line-space the platen, of means including a clutch and an epicyclic train of gearing whereby the movement of said member in one direction causes the platen to be line-spaced, said train including an annular gear concentric with said axle and fixed against rotation, an arm keyed to said axle and carrying a pinion meshing with said annular gear, a second pinion rigidly connected to and alongside of the first pinion and concentric therewith, and a gear meshing with said second pinion and loosely mounted upon said platen-axle, said last-mentioned gear constituting the driver of said train, the driven portion of said clutch being connected to the driver-gear, the driving portion of said clutch being revolute about said axle and operatively connected to said reciprocatory member, and a cylindrical shell surrounding and substantially covering said train of gearing and clutch, said cylindrical shell being also rigidly connected to the driver-gear of said train and serving as a finger-piece which may be manipulated for slow rotation of said platen, said train being proportioned so that the movement of said driver-gear is substantially greater than the resultant movement of said platen.

14. In a variable line-spacing mechanism for a revolute typewriter-platen keyed to an axle, the combination with a reciprocatory member operable for line-spacing said platen, said member mounted for movement transversely of said axle, and means whereby the movement of said member in one direction line-spaces said platen, of means for limiting the stroke of said member to effect different extents of line-spacing, said last-mentioned means including a U-shaped element having spaced-apart sides fulcrumed and bearing upon said axle, one side having a stepped edge forming a predetermined number of stops, said reciprocatory member having a portion which reacts against whatever stop is selected and being normally spring-pressed against said stop, the other side of said element having detent-notches or their equivalent, said other side also having a finger-piece extending therefrom whereby the rotation of said element to different stop positions is facilitated, and a spring-pressed detent co-operating with said notches to hold said element in different positions depending on the stop selected.

15. In a variable line-space mechanism for a revolute typewriter-platen keyed to an axle, the combination with a platen-frame having an end member with a top surface and an inner side, said side extending at right angles to said axle and facing the end of said platen, a reciprocatory member operable for line-spacing said platen and mounted for movement transversely of said axle, and means whereby the movement of

said member in one direction line-spaces said platen, of means for limiting the movement of said member to effect different extents of line-spacing, said last-mentioned means including a U-shaped element having spaced-apart sides fulcrumed and bearing upon a portion of said axle outside the platen-frame end member, one side of said element having a stepped edge forming a predetermined 10 number of stops, said reciprocatory member having a portion which reacts against whatever stop is selected and being normally spring-pressed against said stop, the other side of said element having detent-notches 15 or their equivalent, said other side also having a finger-piece extending through an opening in the platen-frame end member so as to extend along the inner side of said end member and to a point sufficiently above the 20 top surface of said member to permit free manipulation of the finger-piece, and a spring-pressed detent co-operating with said notches to hold said element in different positions depending upon the stops selected.

25 16. In a variable line-space mechanism, the combination with a typewriter-platen keyed to an axle, and a platen-frame having an end member, of a reciprocatory slide operable for line-spacing, a fixture attached 30 to or forming part of said end member and wherein said slide is retained and guided for movement transversely of said axle, a member forming a circular rack whose axis extends perpendicularly to the direction of 35 movement of said slide, said axis being embodied in a pivot supported by said fixture and end member, a pin shiftably mounted in said slide and connecting said slide and circular rack-member for joint reciprocatory 40 movement, an oscillatory member fulcrumed upon the platen-axle and driven by said rack, said last-mentioned member carrying a dog or pawl, an epicyclic train of gearing upon said axle driven from one end by said 45 dog or pawl in one direction of the movement of said slide and rack, the other end of said train being connected to said platen-axle, and a fixed stop against which said pawl or dog reacts at the end of said last- 50 mentioned movement, thereby to prevent overthrow movement of the platen.

55 17. In a variable line-space mechanism, the combination with a typewriter-platen keyed to an axle, of a reciprocatory slide 60 operable for line-spacing, said slide being retained and guided for movement transversely of said axle, a member forming a circular rack whose axis extends perpendicularly to the direction of movement of said slide, a pin shiftably mounted in said slide and connecting said slide and circular rack 65 for joint reciprocatory movement, an oscillatory member fulcrumed upon the platen-axle and driven by said rack, said last-mentioned 70 member carrying a spring-pressed toothed

75 dog or pawl, an epicyclic train of gearing upon said axle driven from one end by said pawl or dog in one direction of the movement of said slide and rack, the driven end of said train having a toothed member engageable by said dog or pawl, the other end of said train being connected to said platen- 80 axle, and a fixed stop against which said pawl or dog reacts at the end of said last-mentioned movement, thereby to cause said pawl or dog to positively interlock with the toothed member at the end of said train and prevent overthrow movement of the platen. 85

90 18. In a line-spacing mechanism for a typewriter of the character described, the combination with a revoluble platen, a shift- 95 able platen-frame in which is journaled an axle to which said platen is keyed, and a letter-feeding carriage carrying said platen-frame, of a line-space lever mounted upon 100 said carriage, a reciprocatory slide operable by said lever and mounted in said platen-frame for movement in a direction trans- 105 verse of said axle, an end of said slide abut- 110 ting an arm of said lever in a manner to permit case-shifting of said platen-frame, a second reciprocatory slide, carried by said platen-frame, mounted alongside said first 115 slide and connected thereto by an intermediate pinion also carried by said platen-frame, each slide being provided with a rack which said pinion engages, a circular 120 rack-member mounted on a pivot carried by said platen-frame, said circular rack-member being disposed alongside said second slide, a pin shiftably mounted upon said second slide and connecting said second slide to said circular rack-member for joint reciprocatory movement, said second slide carrying means for shifting said 125 pin at will to change its position upon said slide relative to the pivot of said circular rack-member thereby to vary the movement of said member for any given movement of said slide, an oscillatory element 130 fulcrumed upon the platen-axle and driven by said circular rack-member, said oscillatory element carrying a spring-pressed pawl or dog, an epicyclic train of gearing mounted upon the platen-axle and driven from one 135 end by said pawl or dog in one direction of movement of said slide and rack, the other end of said train being connected to said platen- 140 axle, means whereby said pawl or dog is normally held disengaged from said train of gearing, and whereby said pawl or dog is caused to engage said train at the beginning of the line-spacing stroke of said oscillatory element, and whereby also said pawl or dog is caused to be disengaged from said train at the beginning of the reverse stroke of said element, a fixed stop against which said pawl or dog reacts at the end of said last-mentioned line-spacing stroke, thereby 145 to prevent overthrow movement of the plat- 150

en, and a cylindrical shell surrounding and substantially covering said train of gearing and oscillatory member, said cylindrical shell being also rigidly connected to the driven end of said train and serving as a finger-piece which may be manipulated for slow rotation of said platen, said train being proportioned so that the movement of the driven end of said train is substantially greater than the resultant movement of said platen.

19. In a line-spacing mechanism for a typewriter of the character described, the combination with a revoluble platen, a shiftable platen-frame in which is journaled an axle to which said platen is keyed, and a letter-feeding carriage carrying said platen-frame, of a line-space lever mounted upon said carriage, a reciprocatory slide operable by said lever and mounted in said platen-frame for movement in a direction transverse of said axle, and end of said slide abutting an arm of said lever in a manner to permit case-shifting of said platen-frame, a second reciprocatory slide carried by said platen-frame, mounted alongside said first slide and connected thereto by an intermediate pinion also carried by said platen-frame, each slide being provided with a rack which said pinion engages, a circular rack-member mounted on a pivot carried by said platen-frame, said circular rack-member being disposed alongside said second slide, a pin shiftably mounted upon said second slide and connecting said second slide to said circular rack-member for joint reciprocatory movement, said second slide carrying means for shifting said pin at will to change its position upon said slide relative to the pivot of said circular rack-member, thereby to vary the movement of said member for any given movement of said slide, an oscillatory element fulcrumed upon the platen-axle and driven by said circular rack-member, said oscillatory element carrying a spring-pressed pawl or dog, an epicyclic train of gearing mounted upon the platen-axle and driven from one end by said pawl or dog in one direction of movement of said slide and rack, the other end of said train being connected to said platen-axle, means whereby said pawl or dog is normally held disengaged from said train of gearing, and whereby said pawl or dog is caused to engage said train at the beginning of the line-spacing stroke of said oscillatory element, and whereby also said pawl or dog is caused to be disengaged from said train at the beginning of the reverse stroke of said element, a fixed stop against which said pawl or dog reacts at the end of said last-mentioned line-spacing stroke, thereby to prevent overthrow movement of the platen, a cylindrical shell surrounding and substantially covering said train of gear-

ing and oscillatory member, said cylindrical shell being also rigidly connected to the driven end of said train and serving as a finger-piece which may be manipulated for slow rotation of said platen, said train being proportioned so that the movement of the driven end of said train is substantially greater than the resultant movement of said platen, and settable means whereby the movement of said second slide may be limited to predetermined extents thereby to selectively effect a single line-space unit of platen movement or predetermined multiples of said unit.

20. The combination with a revoluble typewriter-platen keyed to an axle mounted in a platen-frame having an end member, a fixture attached to or forming part of said end member, of a circular rack mounted in said fixture for reciprocatory movement and operable to line-space the platen, an oscillatory member driven by said circular rack and fulcrumed upon said platen-axle, a spring-pressed pawl or dog carried by said oscillatory member, an epicyclic train of gearing mounted upon said platen-axle, the driving end of said train having a ratchet-wheel which may be engaged by said pawl or dog, the other end of said train keyed to said platen-axle, an annularly-shaped piece revolvably mounted concentric with the platen-axle and frictionally held in an extension of the aforesaid fixture, said piece having an inclined edge which normally holds the pawl disengaged from the ratchet-wheel, said oscillatory member which carries said pawl engaging the annular piece for joint rotation in such manner that there may be by reason of the friction of said annular piece a relative rotary movement between said annular piece and oscillatory member sufficient to cause the pawl to engage said ratchet-wheel at the beginning of the line-space stroke of said oscillatory member and to disengage said pawl and ratchet-wheel at the beginning of the return stroke of said oscillatory member, said annularly-shaped piece having the aforesaid inclined edge to effect said engagement or disengagement during said relative rotary movement, and a second annularly-shaped piece also frictionally mounted concentric with the platen-axle upon the aforesaid extension of said fixture, said annular pieces being retained in grooves formed concentric with the platen-axle in circularly-shaped portions forming part of said fixture-extension, said portions having central holes forming an outboard bearing for the platen-axle, the second annular piece engaging said ratchet-wheel and serving as a brake therefor, said annular pieces being made of thin resilient material to secure lightness and being warped out of flat shape to secure by means of said resilience and warping the desired

friction between said pieces and said grooves.

21. A universal variable line-space mechanism for a revolute typewriter-platen, including, in combination, a reciprocatory line-space lever or operator, a pair of reciprocatory members, one of which is a segment pivotally mounted on a fulcrum, a shiftable pin-and-slot connection joining said members for joint reciprocatory movement, including a slot in each of said members and one pin extending into both slots, means effective upon said connection for changing at will the point of application of said connection relative to said fulcrum, thereby to vary the movement of one member in respect to a given movement of the other member, means connecting said latter other member to said line-space lever or operator, means whereby the movement of the member whose movement is thus variable is translated into line-space rotation of the platen, said translating means including a pinion meshing with said segment and forming therewith a movement-multiplying train, a pawl-and-ratchet mechanism driven by said train, a movement-reducing train between said pawl-and-ratchet mechanism and said platen, and means for regulating the stroke of said line-space lever.

30 22. The mechanism set forth in claim 21, in combination with an indicating device responsive to the shifting of said connection by which differences in the distances of said point of application from said fulcrum and corresponding line-spacing may be gaged.

35 23. A universal line-spacing mechanism for a revolute typewriter-platen, including, in combination, a reciprocatory line-space lever or operator, a circular rack mounted coaxially with the platen for independent rotation, a pivotally mounted reciprocatory segment meshing with said circular rack, a shiftable connection joining said lever or operator and segment for joint reciprocatory movement, means effective upon said connection for changing at will the point of application of said connection to said segment relative to the fulcrum thereof, thereby to vary the movement of said segment and circular rack for any given movement of said operator, and means whereby the movement of said circular rack in one direction is translated into line-space rotation of the platen.

40 24. The mechanism set forth in claim 23, in combination with a stop-device for predetermined the given movement of the reciprocatory line-space lever or operator according to different predetermined multiples of the line-space rotation established by adjustment of the shiftable connection.

45 25. A universal line-spacing mechanism for a revolute typewriter-platen, including, in combination, a reciprocatory line-space lever or operator, a circular rack mounted coaxially with the platen for independent

50 rotation, a connecting train joining said operator and circular rack for joint reciprocatory movement, an adjustable device effective upon said train for micrometrically varying at will the movement of said circular rack derived through said train from a given movement of said operator, and means whereby the movement of the circular rack in one direction is translated into line-space rotation of the platen.

55 26. A universal line-spacing mechanism for a typewriter-platen, including, in combination, with an axle on which the platen is mounted, a circular rack mounted for independent rotation around said axle, a pivotally mounted reciprocatory segment meshing with said circular rack, a reciprocatory driver mounted for movement parallel to said segment, a pin-and-slot connection joining said driver and segment for joint reciprocatory movement, means effective upon said connection for varying at will the point of application of said connection to said segment, thereby to vary the movement of said segment for any given movement of the driver, and means whereby the movement in one direction of said circular rack about the platen-axle is translated into line-spacing rotation of the platen.

60 27. In a universal line-spacing mechanism for a typewriter-platen, the combination with a case-shifting frame in which a platen-axle is journaled, and a letter-feeding carriage carrying said case-shifting frame, of a circular rack mounted for independent rotation around said axle, a pivotally mounted reciprocatory segment meshing with said circular rack, a reciprocatory driver mounted for movement parallel to said segment, a pin-and-slot connection joining said driver and segment for joint reciprocatory movement, a reciprocatory line-space lever or operator carried by the letter-feeding carriage and operatively connected to said driver in a manner to permit movement of said case-shifting frame, said driver being mounted on said case-shifting frame, means effective upon said pin-and-slot connection for varying at will the point of application of said connection to said segment, thereby to vary the movement of said segment for any given movement of the driver, and means whereby the segment-driven movement, in one direction, of said circular rack about the platen-axle is translated into line-spacing rotation of the platen.

65 28. A universal line-spacing mechanism for a revolute typewriter-platen, including, in combination, a reciprocatory operating member, a fine-toothed ratchet-wheel-and-pawl connection between said operating member and the platen, an element having a lost-motion connection to said operating member, and means for frictionally controlling said element so that it moves in

- unison with said operating member throughout most of the stroke of said member in either direction, but lags behind said member at the initial portion of either stroke 5 until the lost motion is overcome, the pawl and frictionally controlled element having provision whereby the relative movement effected between said frictionally controlled element and the reciprocatory member by said lost motion causes the pawl and ratchet-wheel to be engaged and disengaged at the beginning of the line-space and reverse strokes respectively of said member, said provision also effective to keep the ratchet-wheel and pawl disengaged at the end of said reverse stroke so that the platen may be rotated independently in either direction. 10
29. A universal line-spacing mechanism for a revoluble typewriter-platen, including, 20 in combination, a reciprocatory operating member, a one-way clutch-connection between the platen and said operating member so that the latter is effective only in one direction of its movement to rotate said 25 platen, an element of light weight having a lost-motion connection to said operating member, and means for frictionally controlling said element so that it moves in unison with said operating member throughout 30 out most of the stroke of said member in either direction, but lags behind said member at the initial portion of either stroke until the lost motion is overcome, said clutch and frictionally controlled element having 35 provision whereby the relative movement effected between said frictionally controlled element and the operating member by said lost motion causes said clutch to be engaged and disengaged at the beginning of the line- 40 space and reverse strokes respectively of said member, said provision also effective to keep said clutch disengaged at the end of said reverse stroke so that the platen may be rotated independently in either direction, said 45 frictionally controlled element being of light weight, as, for example, the thin light annular piece 92, so that it has not enough inertia to take up the lost motion and cause re-engagement of the clutch at the end of 50 the reverse stroke of said member.
30. A universal line-spacing mechanism for a revoluble typewriter-platen, including, 55 in combination, a fine-toothed ratchet-wheel connected to the platen, a reciprocatory operating member, a ratchet-wheel pawl pivotally mounted on said member, an element having a lost-motion connection to said member, and means for frictionally controlling 60 said element, so that it moves in unison with said operating member throughout most of the stroke of said member in either direction, but lags behind said member during the initial portion of either stroke until the lost motion is overcome, said 65 pawl and frictionally-controlled element
- having provision whereby they co-operate so that the relative movement effected between said frictionally-controlled element and the operating member by said lost motion causes said pawl to engage and be disengaged from 70 said ratchet-wheel at the beginning of the line-space and reverse strokes respectively of said member, said provision also effective to keep said pawl disengaged at the end of said reverse stroke, so that the platen may be 75 rotated independently in either direction. 80
31. A universal line-spacing mechanism for a revoluble typewriter-platen, including, 85 in combination, a fine-toothed ratchet-wheel connected to the platen, a reciprocatory operating member, a ratchet-wheel pawl pivotally mounted on said member, an element having a lost-motion connection to said member, and means for frictionally controlling 90 said element, so that it moves in unison with said operating member throughout most of the stroke of said member in either direction, but lags behind said member during the initial portion of either stroke until the lost motion is overcome, said frictionally-controlled element having a cam and said pawl having provision for co-operating with said cam, so that the relative movement effected between said frictionally-controlled element and the reciprocatory member by 95 said lost motion causes said pawl to engage and be disengaged from said ratchet-wheel at the beginning of the line-space and reverse strokes respectively of said member, said cam also effective to keep said pawl disengaged at the end of said reverse stroke so that the platen may be rotated independently 100 in either direction. 105
32. A universal line-spacing mechanism for a revoluble typewriter-platen, including, 110 in combination, a fine-toothed ratchet-wheel connected to the platen, a reciprocatory operating member, a ratchet-wheel pawl pivotally mounted on said member, an element having a lost-motion connection to said member, and means for frictionally controlling 115 said element, so that it moves in unison with said operating member throughout most of the stroke of said member in either direction, but lags behind said member during the initial portion of either stroke until the lost motion is overcome, said pawl and frictionally-controlled element being provided with camming devices so that the relative movement effected between said frictionally-controlled element and the operating member by said lost motion causes said pawl to engage and be disengaged from said ratchet-wheel at the beginning of the line-space and reverse strokes respectively of said member, 120 said provision also effective to keep said pawl disengaged at the end of said reverse stroke so that the platen may be rotated independently in either direction. 125
33. A universal line-spacing mechanism 130

for a revoluble typewriter-platen, including, in combination, a fine-toothed ratchet-wheel connected to the platen, a reciprocatory operating member, a stationary member having a surface coextensive with and adjoining the path described by said member, and a pawl pivotally mounted on said member and having a friction connection with said surface, said friction connection and pawl 10 co-operating so that at the initial portions of line-space and reverse strokes of said reciprocatory member said pawl respectively engages and is disengaged from said ratchet-wheel and is also kept disengaged at the end 15 of said reverse stroke so that the platen may be rotated independently in either direction.

34. The combination with a revoluble typewriter-platen, of an epicyclic gear-train for slowly rotating said platen by hand to 20 finely adjust a work-sheet to the printing line, said train including a low-speed member operatively connected to the platen, a manually-rotatable high-speed member, and intermediate members, including a fixed member, to translate the high speed of the manually-rotatable member into the low speed of the member connected to the platen.

35. The combination with a revoluble typewriter-platen, of an epicyclic gear-train 30 for slowly rotating said platen by hand to finely adjust a work-sheet to the printing line, one end of said gear-train being a low-speed member keyed to said platen, the other end of said train being a manually-operable high-speed member, said train also having intermediate members, including a fixed member, to translate the high speed of the manually-rotatable member into the low speed of the member keyed to the platen- 35 axle, the members of said train being of such character in respect to their points of engagement with one another that said train is not self-locking, and is therefore rotatable from the platen-end, to thereby permit direct rotation of said platen.

36. The combination with a revoluble typewriter-platen, of an epicyclic gear-train for slowly rotating said platen by hand to 50 finely adjust a work-sheet to the printing line, said train including a low-speed member operatively connected to the platen, a manually-rotatable high-speed member, and intermediate members, including a fixed member, to translate the high speed of the manually-rotatable member into the low speed of the member connected to the platen, the manually-operable high-speed member connected to a cylindrical shell which surrounds and thereby substantially encloses 55 said members, said shell also forming a finger-piece for conveniently rotating said high-speed member by hand.

37. The mechanism set forth in claim 34, 60 in combination with a universal line-spacing

mechanism effective to co-operate with said train to line-space the platen.

38. The mechanism set forth in claim 34, in combination with a universal line-spacing mechanism normally disengaged from said train, said mechanism when called into action automatically engaging and disengaging 70 said train to effect line-spacing of the platen.

39. The mechanism set forth in claim 34, in combination with a universal reciprocatory line-spacing mechanism normally disengaged from said train and having a micrometrically adjustable device for varying 75 the line-space at will, said mechanism when called into action automatically engaging said train to line-space the platen in one direction of the movement of said mechanism, and automatically disengaging itself from 80 said train in the reverse direction of said movement.

40. A micrometrically variable line-spacing mechanism for a revoluble typewriter-platen, including, in combination, a reciprocatory line-spacing operator, a circular rack 90 mounted coaxially with the platen for independent rotation, adjustable connecting means whereby said circular rack derives a micrometrically variable movement from a given movement of said operator and whereby said operator and rack reciprocate in unison, a fine-toothed clutch having one side connected to said rack, and a speed-reducing train connecting the other side of said clutch to said platen, said operator and rack connecting means having provision whereby the rotation of said rack is substantially greater than the resultant line-spacing rotation of the platen, so that said greater rotation in conjunction with the fine teeth of the clutch 95 renders the effect of the aliquant relation of the clutch-teeth spacing to the line-spacing negligible, said speed-reducing train translating the greater clutch-movement into line-spacing rotation of the platen. 100

41. The combination with a revoluble typewriter-platen and a reciprocatory line-spacing mechanism therefor, having provision for micrometrically varying the line-spacing, said mechanism also having a fine-toothed clutch for rendering advance and reverse strokes of said mechanism respectively effective and ineffective to rotate the platen, said mechanism also having provision for rotating said clutch more than the required 115 rotation of the platen so that the larger rotation in conjunction with the fine clutch-teeth renders the effect of the aliquant relation of the clutch-tooth spacing to the line-spacing negligible, of an epicyclic gear-train 120 connecting said clutch and platen and translating the greater rotation of the clutch into line-space rotation of the platen. 125

42. The combination with a revoluble typewriter-platen and a reciprocatory line- 130

spacing mechanism therefor, having provision for micrometrically varying the line-spacing, said mechanism also having a fine-toothed clutch rotatable coaxially with the 5 platen-axis, said clutch rendering advance and reverse strokes of said mechanism respectively effective and ineffective to rotate the platen, said mechanism also having provision for rotating said clutch more than the 10 required rotation of the platen so that the larger rotation in conjunction with the fine clutch-teeth renders the effect of the aliquant relation of the clutch-tooth spacing to the line-spacing negligible, of an epicyclic 15 gear-train operable about the platen-axis and connecting said clutch to the platen, said train translating the larger clutch-rotation into line-space rotation of the platen.

43. The combination with a revolute 20 typewriter-platen and a reciprocatory line-spacing mechanism therefor, having provision for micrometrically varying the line-spacing, said mechanism also having a fine-toothed clutch for rendering advance and 25 reverse strokes of said mechanism respectively effective and ineffective to rotate the platen, said mechanism also having provision for rotating said clutch more than the required rotation of the platen so that the 30 larger rotation in conjunction with the fine clutch-teeth renders the effect of the aliquant relation of the clutch-tooth spacing to the line-spacing negligible, of an epicyclic gear-train connecting said clutch and platen 35 and translating the greater rotation of the clutch into line-space rotation of the platen, said train including a gear mounted coaxially with the platen-axis for independent rotation and connected with said clutch, a 40 gear fixed against rotation and concentric with said platen-axis, an arm keyed to the platen for rotating said platen, and connected pinions revolute by said arm around the platen-axis, one of said pinions meshing 45 with said first-mentioned gear and another pinion meshing with said fixed gear.

44. The combination with a revolute 50 typewriter-platen and a reciprocatory line-spacing mechanism therefor, having provision for micrometrically varying the line-spacing, said mechanism also having a fine-toothed clutch for rendering advance and reverse strokes of said mechanism respectively effective and ineffective to rotate the platen, said mechanism also having provision for rotating said clutch more than the required rotation of the platen so that the 55 larger rotation in conjunction with the fine clutch-teeth renders the effect of the aliquant relation of the clutch-tooth spacing to the line-spacing negligible, of an epicyclic gear-train connecting said clutch and platen and translating the greater rotation of the clutch into line-space rotation of the platen, said 60 train including a gear mounted coaxially

with the platen-axis for independent rotation and connected with said clutch, a gear fixed against rotation and concentric with the platen-axis, an arm keyed to the platen for rotating said platen, and connected pinions revolute by said arm around the platen-axis, one of said pinions meshing with said first-mentioned gear, and another pinion meshing with said fixed gear, said 70 gears and pinions proportioned and arranged so that one gear engages its pinion from one side of the pinion-axis and the other gear engages its pinion from the other side of said pinion-axis to thereby avoid locking of said train against independent 75 rotation of the platen.

45. In a line-spacing mechanism for a revolute typewriter-platen, the combination with a platen-axle and a reciprocatory line-spacing driver, of a stop-device for determining different ranges of movement of said driver to vary the line-spacing, said stop-device including a shiftable segment that for compactness of the mechanism is fulcrumed upon or coaxial with the platen-axle, said 90 segment having steps at different distances from its fulcrum, said driver being mounted and having provision so that its movement may be arrested according to the different positions determined by said steps. 95

46. The mechanism set forth in claim 45, in combination with means for retaining said stepped segment in its different stop-positions.

47. The mechanism set forth in claim 45, in combination with a spring-pressed detent-device, the stepped segment of said claim 100 45 having provision to co-operate with said detent-device so as to be retained in its different stop-positions. 105

48. A universal line-spacing mechanism for a revolute typewriter-platen, including, in combination, a reciprocatory driver, adjustable connecting means between the driver and platen, whereby the movement of said 110 driver in one direction is translated into variable line-space rotation of the platen, said platen-rotation being thus variable for any given movement of the driver, and means for setting said given movement, said latter 115 means including a stop-device co-operating to arrest the driver at a fixed position at the end of the movement of said driver in one direction and also including a shiftable segment having a fulcrum that for compactness of the mechanism is coaxial with the platen, said segment having steps at different distances from said fulcrum, said driver having provision so that its movement in the other direction may be arrested at the 120 different positions determined by said steps. 125

BURNHAM C. STICKNEY.
